Primary Examiner — Cathron Brooks*Assistant Examiner* — Melanie Pellegrini(74) *Attorney, Agent, or Firm* — TraskBritt, P.C.(57) **CLAIM**

The ornamental design for a retractable lanyard, as shown and described.

DESCRIPTION

FIG. 1 is a perspective view of a retractable lanyard showing my new design;

FIG. 2 is a front view of the retractable lanyard shown in FIG. 1;

FIG. 3 is a rear view of the retractable lanyard shown in FIG. 1;

FIG. 4 is a first side view of the retractable lanyard shown in FIG. 1;

FIG. 5 is a second side view of the retractable lanyard shown in FIG. 1;

FIG. 6 is a perspective view of a third embodiment of a retractable lanyard showing my new design;

FIG. 7 is a front view of the retractable lanyard shown in FIG. 6;

FIG. 8 is a rear view of the retractable lanyard shown in FIG. 6;

FIG. 9 is a first side view of the retractable lanyard shown in FIG. 6; and,

FIG. 10 is a second side view of the retractable lanyard shown in FIG. 6.

The broken lines shown in the drawings illustrate portions of the retractable lanyard that form no part of the claimed design.
